DRIER FOR SHEETING

William Owen, Pittsburgh, Pa., assignor to Pittsburgh Plate Glass Company, Allegheny County, Pa., a corporation of Pennsylvania

Application June 22, 1938, Serial No. 215,142

10 Claims. (Cl. 34—12)

The invention relates to an apparatus for drying sheet material, such as the synthetic resin sheeting employed in the manufacture of safety glass, one of which is a vinyl acetal. This material is supplied in rolls and the apparatus is designed to unwind the material, dry it and against wind it into a roll, thus bringing it to the moisture content necessary for satisfactory lamination with glass sheets. The primary objects of the invention are the provision of a very compact apparatus of low cost which will carry out the steps above recited, and in which the sheeting during its manipulation in carrying it through the drier will be free from strain tending to stretch and thin any portions thereof. Certain embodiments of the invention are shown in the accompanying drawings, wherein:

Figure 1 is a plan view. Fig. 2 is a transverse section on the line II—II of Fig. 1. Fig. 3 is a section taken at right angles to a section of Fig. 2. Fig. 4 is a horizontal section on an enlarged scale through a part of the drive mechanism. Figs. 5, 6 and 7 are detail views on an enlarged scale showing a modification, Fig. 5 being a plan view, Fig. 6 a section on the line VI—VI of Fig. 5, and Fig. 7 a side elevation. And Figs. 8 and 9 are detail views illustrating another modification, Fig. 8 being a front elevation and Fig. 9 a side elevation.

Referring to the drawings, the casing 9 of the drier is of cylindrical shape and includes a double bottom wall 10, 11 and a double top wall 12, 13. The side walls comprise two plates 14 and 15 with the space 16 therebetween to provide for an outflow of air as hereinafter explained. At the center of the casing is a vertical standard 17, whose wall is perforated throughout, as indicated in Fig. 2, the perforations being employed for circulation purposes. The walls 10, 12 and 14 are also similarly perforated for circulation purposes. The supply of air is furnished from the blower 18 driven from the motor 19, such air being brought through the eye of the blower through a suitable air intake heater 20. The air which is thus supplied to the space 21 passes in part vertically into the casing through perforations 21a in the bottom wall 10, and in part passes up into the standard 17 and then flows laterally through the perforated wall of the standard and is discharged to the space 16 through the inner wall 14 of the casing which is perforated throughout so as to give a good distribution of the air. A part of the air also flows upward to the space 22 through the perforated top wall 12 of the casing. The

stack 24 constitutes an outlet from the space 22. This arrangement provides for a thorough circulation of air from the center of the casing outward through all parts of the sheeting which is carried therethrough, as later described, and also upward through the folds of such sheeting.

The standard 17 carries at its upper end a post 25 on which a cylindrical support 26 is mounted for rotation, such support being provided with the casters 27 running on the top of the casing 10 17 and with the two sets of ball bearings 28, 29. Extending radially of the support 26 and secured rigidly thereto are a series of arms 29, 30, 31, 32, etc., which arms are employed to carry the sheeting in festoons as more fully set forth later. The support 26 is, in the operation of the machine, given a step by step rotation with periods of rest between each movement, in which periods of rest, and also while the support is rotating, the sheeting is fed into the drier and removed therefrom, the major portion of a festoon of the sheeting being inserted at each rest period and the major portion of another festoon which has made the circuit is removed. In order to accomplish the rotation of the member 26 carrying the arms, the upper edge of the member is provided with a set of ratchet teeth 33 which are engaged by a pawl 34 (Fig. 3) carried on an arm 35, the pivot 36 being guided horizontally in the slot 37 in one of the structural members constituting a part of the top of the casing. The arm 35 is reciprocated from a crank disc 39 which is driven from a motor 40 seated on the top of the casing through the intermediary of suitable reduction gearing. This gearing includes a reducer in the casing 41, which drives the shaft 42 (Fig. 1), the sprocket 43 on the shaft driving the sprocket 44 through a chain, and the intermittently driven clutch device 45, which gives a pause of suitable length between the reciprocations of the connecting rod.

One form of device for giving the intermittent movement required is shown in Fig. 4. The gear 46 keyed to the shaft 47 drives the gear 48, which is loose on the shaft 42. Keyed to the shaft alongside of the gear 48 is a clutch member 50 which cooperates with an interfitting clutch member 51, the latter being loose on the shaft. The hub of the member 51 extends through the bearing support 52 and has keyed thereto at the left of such support the crank disc 39. The key 53 serves to lock the clutch members 50 and 51 together during those intervals at which the crank disc is to be rotated. The key is

carried in a groove in the wall of the member 51 with a leaf spring 54 on one side tending to force it outward into engagement with a groove in the wall of the member 50. The position of the key is governed by the lever 55 normally urged upward by the spring 56, but adapted to be moved downward by the cam 57 attached to the side of the gear 48. At each revolution, therefore, of the slowly moving gear 48, the parts 10 assume the position shown in the drawings with the key 52 engaging the grooves in both clutch members, so that they are locked together, while the shaft 42 and crank disc 39 make one revolution. When this revolution is completed (the 15 cam 57 now being out of registry with the lever 56, so that the lever is held in its up position by the spring 56), the cam part 58 on the lever engages the key and pushes it up into its groove and out of engagement with the clutch member 20 50, so that the member 51 and the crank disc stop rotating. The drive of the shaft 42 which feeds the material to be dried is thus continuous, while the drive of the crank disc 39 which rotates the support and its radial arms is intermittent.

The roll of sheeting 59 which is to be dried is mounted upon a shaft 60 (Fig. 3) which fits at its ends into a pair of slots 61 in the plates 62 and 63, such shaft 60 extending substantially radially of the casing as indicated in Fig. 1. The sheeting after drying, is delivered from the casing to form the roll 64, a shaft 65 being provided to carry this roll of sheeting, and such shaft being located adjacent to and parallel to the shaft 35 60 which carries the roll 59. This shaft 65 is also mounted in slots 66 similar to the slots 61. The rolls 59 and 64 are driven from a pair of feed rolls 67 and 68, which are parallel to the shafts 60 and 65 and are driven from the motor 40 through the intermediary of the shaft 42, the sprocket chain 69 passing around sprockets 70 and 71 and the gears 72, 73 and 74. The gear 72 is mounted on the shaft which carries the sprocket 71, while the gear 73 is an idler interposed between the 40 gears 72 and 74, so that the shafts 61 and 65 are both driven in the same direction, which as indicated in Fig. 3, is counterclockwise. The sheeting is thus fed down into the casing from the roll 59, while the other end of the sheeting is fed 45 upwardly from the casing and wound onto the roll 64. Provision is thus made for feeding the sheeting into and out of the casing by the gripping pressure between the rolls 59 and 67 and between the rolls 64 and 68, and it will be seen that 50 the mounting of the shafts 60 and 65 in the inclined slots provides for giving the necessary pressure to grip the sheeting. Also that this arrangement is self-adjusting, in that the character of the feed is not affected, due to the exhaustion of 55 the material from the roll 59 or to the building up 60 of the roll 64. Spring clips 29a and 31a depending from the top wall of the casing are provided, as indicated in Figs. 2 and 3, such clips serving to clamp the festoons to two of the radial arms, 65 when such arms are in the position of Fig. 3. At such time, the festoon A is clamped at its forward edge to the arm 31, while the festoon B is clamped at its rear edge to the arm 29. This prevents slippage over the arms due to unbalanced festoon weight while the festoon A is being completed and the festoon B is being removed.

The intermediate step by step movement of the supporting member 26 carrying the arms provides a period of rest between each movement 70 and it is during this period of rest that the major

portion of a festoon, such as the one marked A in Fig. 3, is fed down into the space between the arm 31 and the arm 30 from the roll 59. At this same period of rest, the major portion of the festoon B is fed from the space between the arm 30 and the arm 29, the feeding up of such festoon being completed at the same time that the festoon A is completed. When these feeding actions are nearly completed, the rotary movement of the member 26 carrying the radial arms is started again and continues until the arm 30 shifts over to the position just occupied by the arm 31 and the arm 29 shifts over to the position just occupied by the arm 30, after which the cycle is re-peated.

It will be noted that the upper sides of the radial arms over which the sheeting is draped are inclined downwardly from the horizontal from their inner to their outer ends. The purpose of this is to provide for the festooning of the material without any stretching of the outer edges of the sheeting, such as would necessarily occur, if the tops of the arms were located in horizontal planes. When the arms are inclined downward at the proper degree, as illustrated, the total 25 length of the outer edge of the sheeting lying in the casing is the same as the total length of the inner edge, so that there is no tendency to deform the material by stretching it along its outer edge.

Referring to the modification shown in Figs. 5, 30 6 and 7, it is desirable that there should be some shifting of the festoons at their areas of support upon the arms, otherwise these portions would not be exposed to the same drying action as the balance of the sheet and the sheet would not be 35 exposed throughout its entire length to the same stretching action. Provision is, therefore, made in this modification for giving the sheeting a movement in the direction of its length over the arms as it travels through the drier. This result 40 is accomplished by mounting the shafts 75, which act as the arms, for rotation in the hub 76 and providing gear means for giving these shafts a slight rotary movement during the periods in which the arms are being moved around the axis 45 of the supporting member 26. Each of the shafts is, therefore, provided at its inner end with a bevel gear 77 and these gears mesh with a gear 78 which is fixed to the top of the standard 17 and to the post 79. The hub 76 is provided with 50 ratchet teeth 33a which are engaged by a pawl similar to the pawl 34 (Fig. 3) and similarly operated. It follows that as the hub 76 rotates about the axis of the casing, the shafts 75 are rotated and the sheeting is fed over the tops of the 55 arms a substantial distance during the period of rotation of a festoon about the axis of the casing.

Figs. 8 and 9 illustrate a modification, in which provision is made for feeding a number of strips of sheeting 80, 81, and 82 simultaneously into 60 and out of the casing. In this case, the various rolls of material are mounted on the same shaft 83, which is driven as heretofore described, and the rolls of material rest upon the pairs of rolls 84 and 85, and 86 and 87, the rolls 85 and 86 65 being the feed rolls corresponding to the rolls 67 and 68 of the structure heretofore described, and the rolls 84 and 87 being idler rolls. In this case, the rolls 84 and 87 are provided with flanges 88 for guiding the sheeting. In this case, also, the 70 additional driven roll 89 may be employed lying between the rolls 85 and 86. The operation is in all respects similar to that heretofore described. What I claim is:

1. In a drier for sheeting, a casing, a vertical 75

- support mounted for rotation in the casing and provided with a series of spaced radially extending arms, a rotary member above the casing also extending radially with respect to the vertical support for carrying a roll of the sheeting to be dried, a second rotary member above the casing adjacent and parallel to the first rotary member and adapted to receive and roll up the sheeting after it has passed through the casing, means for giving the vertical support a step by step movement of rotation, each step being equal in distance to the spaces between the radial arms, and means for rotating said rotary members so that a festoon of sheeting is fed between a pair of arms by the first member and at the same time another festoon of sheeting is fed by the second member from the space between a pair of arms which have completed a circuit through the casing.
2. In a drier for sheeting, a casing, a vertical support mounted for rotation in the casing and provided with a series of spaced radially extending arms, a rotary member above the casing also extending radially with respect to the vertical support for carrying a roll of the sheeting to be dried, a second rotary member above the casing adjacent and parallel to the first rotary member and adapted to receive and roll up the sheeting after it has passed through the casing, means for giving the vertical support a step by step movement of rotation, each step being equal in distance to the spaces between the radial arms, and means for rotating said rotary members so that a festoon of sheeting is fed between a pair of arms by the first member and at the same time another festoon of sheeting is fed by the second member from the space between a pair of arms which have completed a circuit through the casing, the means for rotating said members comprising a motor and a pair of rolls driven thereby, one of which is adapted to engage the roll of sheeting which is fed into the casing and the other of which is adapted to engage the other roll of sheeting which is carried by the second rotary member.
3. In a drier for sheeting, a casing, a vertical support mounted for rotation in the casing and provided with a series of spaced radially extending arms, a rotary member above the casing also extending radially with respect to the vertical support for carrying a roll of the sheeting to be dried, a second rotary member above the casing adjacent and parallel to the first rotary member and adapted to receive and roll up the sheeting after it has passed through the casing, means for giving the vertical support a step by step movement of rotation each step being equal in distance to the spaces between the radial arms, and means for rotating said rotary members so that a festoon of sheeting is fed between a pair of arms by the first member and at the same time another festoon of sheeting is fed by the second member from the space between a pair of arms which have completed a circuit through the casing, the means for rotating said members comprising a motor and a pair of rolls driven thereby, one of which is adapted to engage the roll of sheeting which is fed into the casing and the other of which is adapted to engage the other roll of sheeting which is carried by the second rotary member, said first and second rotary members being mounted for gravity movement toward the members of said pair of rolls.
4. In a drier for sheeting, a casing, a vertical support mounted for rotation in the casing and provided with a series of spaced radially extending shafts, a rotary member above the casing also extending radially with respect to the vertical support for carrying a roll of the sheeting to be dried, a second rotary member above the casing adjacent and parallel to the first rotary member and adapted to receive and roll up the sheeting after it has passed through the casing, means for giving the vertical support a step by step movement of rotation, each step being equal in distance to the spaces between the shafts, means for rotating the shafts as the vertical support rotates, and means for rotating said rotary members so that a festoon of sheeting is fed between a pair of shafts by the first member and at the same time another festoon of sheeting is fed by the second member from the space between a pair of arms which have completed a circuit through the casing.
5. In a drier for sheeting, a casing, a vertical support mounted for rotation in the casing and provided with a series of spaced radially extending arms, a rotary member above the casing also extending radially with respect to the vertical support for carrying a roll of the sheeting to be dried, a second rotary member above the casing adjacent and parallel to the first rotary member and adapted to receive and roll up the sheeting after it has passed through the casing, means for giving the vertical support a step by step movement of rotation, each step being equal in distance to the spaces between the radial arms, and means for rotating said rotary members so that a festoon of sheeting is fed between a pair of arms by the first member and at the same time another festoon of sheeting is fed by the second member from the space between a pair of arms which have completed a circuit through the casing.
6. In a drier for sheeting, a vertical cylindrical casing having its wall perforated throughout, a vertical cylindrical standard at the center of the casing having its wall perforated throughout, means for supplying heated air to the lower end of the standard so that a circulation is provided radially through the casing from the standard to the walls of the casing, a vertical support mounted for rotation on the upper end of the standard and provided with a series of spaced radially extending arms, a rotary member above the casing also extending radially with respect to the support for carrying a roll of the sheeting to be dried, a second rotary member above the casing adjacent and parallel to the first rotary member and adapted to receive and roll up the sheeting after it has passed through the casing, and means for rotating the vertical support and said rotary members in timed relation so that a festoon of sheeting is fed from the first rotary member between each pair of arms as the space between the arms passes such member, and a festoon of the sheeting which has completed the circuit of the casing is simultaneously withdrawn therefrom and wound on the second supporting member.
7. In a drier for sheeting a vertical cylindrical casing having a double wall with a space between the walls and having its inner wall perforated throughout, an outlet from said space to the atmosphere, a vertical cylindrical standard at the center of the casing having its wall perforated throughout, means for supplying heated air to the

lower end of the standard so that a circulation is provided radially through the casing from the standard to the walls of the casing, a vertical support mounted for rotation on the upper end 5 of the standard and provided with a series of spaced radially extending arms, a rotary member above the casing also extending radially with respect to the support for carrying a roll of the sheeting to be dried, a second rotary member 10 above the casing adjacent and parallel to the first rotary member and adapted to receive and roll up the sheeting after it has passed through the casing, and means for rotating the vertical support and said rotary members in timed relation 15 so that a festoon of sheeting is fed from the first rotary member between each pair of arms as the space between the arms passes such member, and a festoon of the sheeting which has completed the circuit of the casing is simultaneously withdrawn therefrom and wound on the second supporting member.

8. In a drier for sheeting, a casing, a vertical support mounted for rotation in the casing and provided with a series of spaced radially extending 25 arms, a rotary member above the casing also extending radially with respect to the vertical support for carrying a roll of the sheeting to be dried, a second rotary member above the casing adjacent and parallel to the first rotary member 30 and adapted to receive and roll up the sheeting after it has passed through the casing, means for giving the vertical support a step by step movement of rotation each step being equal in distance to the spaces between the radial arms, 35 means for rotating said rotary members so that a festoon of sheeting is fed between a pair of arms by the first member and another festoon of sheeting is fed by the second member from the space between a pair of arms which have 40 completed a circuit through the casing, and spring means carried by the casing above the arms, one of which is positioned so as to clamp the sheeting to the upper side of the arm on the forward side of the space to which the festoon 45 is delivered, and the other of which is positioned

so as to clamp the sheeting to the upper side of the arm on the rear side of the space from which the festoon is removed.

9. In a drier for sheeting, a casing, a vertical support mounted for rotation in the casing and 5 provided with a series of spaced radially extending arms, a rotary member above the casing also extending radially with respect to the vertical support for carrying a roll of the sheeting to be dried, a second rotary member above the casing 10 adjacent and parallel to the first rotary member and adapted to receive and roll up the sheeting after it has passed through the casing, and means for rotating the vertical support and said rotary members in timed relation so that a festoon 15 of sheeting is fed from the first rotary member between each pair of arms when each space between a pair of arms is brought adjacent such member and a festoon of the sheeting which has completed the circuit is simultaneously withdrawn 20 therefrom and wound on the second supporting member.

10. In a drier for sheeting, a casing, a vertical support mounted for rotation in the casing and provided with a series of spaced radially extending 25 arms, a rotary member above the casing also extending radially with respect to the vertical support for carrying a roll of the sheeting to be dried, a second rotary member above the casing adjacent and parallel to the first rotary member 30 and adapted to receive and roll up the sheeting after it has passed through the casing, and means for rotating the vertical support and said rotary members in timed relation so that a festoon 35 of sheeting is fed from the first rotary member between each pair of arms when each space between a pair of arms is brought adjacent such member and a festoon of the sheeting which has completed the circuit is simultaneously withdrawn 40 therefrom and wound on the second supporting member, said arms being inclined downwardly from the horizontal from their inner to their outer ends.

WILLIAM OWEN. 45
